UNITED STATES PATENT OFFICE.

JOSEF GRAEF, OF EVERETT, WASHINGTON.

WINDOW-PANE FASTENER.

981,411.

Specification of Letters Patent. Patented Jan. 10, 1911.

Application filed April 5, 1910. Serial No. 553,509.

To all whom it may concern:

Be it known that I, JOSEF GRAEF, a citizen of the United States, residing at Everett, in the county of Snohomish and State of Washington, have invented new and useful Improvements in Window-Pane Fasteners, of which the following is a specification.

This invention relates to improvements in fastening strips for window panes and has 10 for one of its objects the provision of a device of that kind, whereby a pane of glass may be secured in the sash of a window without the employment of putty.

Another object is the provision of a fastening strip formed of a single piece of sheet 15 metal or its equivalent bent into such shape that when applied to the sash of a window it will correspond to the angle between the glass and inner side of the sash and present 20 a neat and attractive appearance.

A further object is the provision of a fastening strip integrally provided with barbs or the like, the said barbs being so located 25 that the strip may be secured to the sash in an expeditious manner.

A still further object is the provision of a packing strip preferably formed of a springy substance and insertible between the inner face of the fastening strip and adjacent 30 surfaces of the pane and sash, whereby the barbs may be driven into the sash to the required depth without danger of breaking the pane.

With these and other objects in view, 35 which will more fully hereinafter appear, the present invention consists in certain novel details of construction and arrangement of parts, hereinafter fully described, illustrated in the accompanying drawings 40 and more particularly pointed out in the appended claims; it being understood that various changes in the form, proportion, size, and minor details of the device may be made, within the scope of the appended claims, 45 without departing from the spirit or sacrificing any of the advantages of the invention.

In the accompanying drawings, forming a 50 part of the specification;—Figure 1 is a plan view of a portion of the blank from which my improved device is constructed. Fig. 2 is a sectional end view approximately on the line 2—2 of Fig. 1 after the blank is folded. Fig. 3 is a view similar to Fig. 2 but show-

ing the fastener applied to a window sash 55 and pane. Fig. 4 is a detail perspective of one end portion of the fastener.

Similar numerals of reference are employed to designate corresponding parts throughout. 60

The device about to be described is formed of a single piece of sheet metal corresponding in length to the pane receiving rabbet of a window sash. A portion of the blank or sheet is illustrated in Fig. 1 where-in it will be seen that the sheet 5 is oblong in contour and has a formed integral with one of its longitudinal sides a plurality of spaced barbs 6. Prior to shaping the sheet to the angle formed by the inner side of 70 the sash and pane, the sheet is bent upon itself longitudinally and at its medial portion, whereby sides 7 and 8 are provided, after which the outer side 7 is, at its medial portion bent outwardly and at right angles 75 as shown at 9. It might here be stated that the barbs 6 are combined with the longitudinal edge of the inner side 8 and are perpendicular to the outwardly bent portion 9. By reference now to Figs. 2 to 4 inclusive, it will be seen that the outwardly bent portion 9 terminates in a marginal flange 10, and adjacent to the juncture of the sides 10 and 8 the metal is bent at right angles, 80 whereby a flange 11 is formed overhanging 85 the inner side member 8 and extending in a direction at right angles to the direction of the flange 10. Reference to Fig. 4 discloses the fact that the barbs 6 project considerably beyond the plane of the longitudinal edge of 90 the flange 10, thus permitting the barbs to enter a wooden sash until the edge of the flange bears on the said sash.

By reference to Fig. 3 it will be seen that the inner surface of the strip formed by the side portion 8 and inner surface of the laterally bent portion 9 is provided with a cushion or packing strip designated in general by the numeral 12. This cushion or packing strip may be formed of rubber or by a mixture of glue and pulp and is shaped to the inner surface of the fastening strip. The thickness of the packing strip corresponds approximately to the width of the flanges 10 and 11, so that when positioned as shown in Figs. 2 and 3 the barbs 6 will extend through the strip, while the opposite sides will bear on the inner surfaces of the 100 105

2 flanges 10 and 11. With this construction it will be manifest when the flange 11 bears on the surface of the pane 13, as shown in Fig. 3 and the barbs 6 move into engagement 5 with the sash that the barbs may be driven home by applying a suitable tool to bear on the laterally bent portion 9 and then hammering the tool in a well-known manner.

From the foregoing it is evident that I 10 have provided a device which is comparatively simple in structure and inexpensive in manufacture, embodying few parts and these so arranged that the danger of derangement will be reduced to a minimum.

15 I claim:—

1. A fastening strip for window panes comprising a metallic plate bent upon itself at its medial portion and in the direction of its length to provide opposite side members one of which is bent laterally at its 20 medial portion and terminates in a lateral flange, the said side members adjacent to their juncture being bent laterally to provide a flange extending in a different direction to the first-named flange, in combination with a packing strip arranged over one 25

face of the plate thus formed with its opposite sides bearing on said flanges.

2. A fastening strip for window panes comprising a metallic plate bent upon itself 30 at its medial portion and in the direction of its length to provide opposite side members one of which is bent laterally at its medial portion and terminates in a lateral flange, the said side members adjacent to 35 their juncture being bent laterally to provide a flange extending in a different direction to the first-named flange, in combination with a packing strip arranged over one 40 face of the plate thus formed with its opposite sides bearing on said flanges, and a plurality of spaced barbs formed with one of the side members and projecting through the said packing strip and extending parallel with the first-named flange. 45

In testimony whereof I affix my signature in presence of two witnesses.

JOSEF GRAEF.
